(57) **CLAIM**

The ornamental design for a serving tray, as shown and described.

DESCRIPTION

FIG. 1 is a top plan view of a serving tray showing my new design:

FIG. 2 is a bottom view thereof;

FIG. 3 is a front elevational view thereof;

FIG. 4 is a rear elevational view thereof;

FIG. 5 is a left side view thereof;

FIG. 6 is a right side view thereof;

FIG. 7 is a front perspective view thereof; and,

FIG. 8 is a rear perspective view thereof.

The broken lines showing is included for the purpose of illustrating environment of the design and forms no part of the claimed design.
